HUGH W. DRIFTMEYER, OF BOSTON, MASSACHUSETTS

TIME CONTROLLED SWITCH

Application filed March 24, 1928. Serial No. 264,486.

My invention relates to time controlled switches for electric circuits.

Its primary object is to provide an efficient and commercially practicable means for automatically closing the lighting circuit on an automobile at a predetermined time, which may be varied by adjustable means.

A secondary object is to provide such a device for use in any electric circuit whereby the circuit may be closed or opened at a predetermined time which may be varied and indicated. A particular advantage of my invention lies in its adaptation for use with an ordinary clock, and preferably an alarm clock. Other advantages lie in the insulation of the device from the clock mechanism; the elimination of spring actuated detents and the like; and in its simplicity of construction and its adaptability to use either as a time controlled circuit closer or breaker.

My invention consists in the novel combination of elements in combination with an ordinary time piece.

In the accompanying specifications and claims and the drawings forming a part thereof, I have described and illustrated a preferred form of my invention.

In the drawings,

Fig. 1 is a face view of an alarm clock with which I have embodied my invention, and in which part of the clock dial is broken away, and the clock mechanism omitted in the interests of simplicity.

Fig. 2 is a side elevation partially in section of my device in connection with a clock of ordinary construction, the timing mechanism of which is concealed, as without novelty.

Fig. 3 is an enlarged sectional elevation, substantially on line 3-3, Fig. 4, of the switch portion of my invention.

Fig. 4 is a section substantially on line 4-4, Fig. 3.

Fig. 5 is a diagram illustrating the application of my invention to the light circuit of an automobile.

In the drawings, A is a clock with dial 10, minute hand 11, and hour hand 12, the usual clock mechanism being employed. To the center arbor 13 of the clock, is secured the

pinion 14, and through the gear train 15, 16, 17, 18, the shaft 19 and the sleeve 20, on which is pressed the minute hand, are rotated in unison. This is the gear train ordinarily employed in an alarm clock, and is here shown in connection with my device, the alarm mechanism being eliminated and only the alarm setting shaft and the gear train being retained. It is here described as, for practical reasons and adaptability to attachment to the instrument board of an automobile, it may be advisable to rearrange the elements in connection with an automobile clock of the usual construction, without affecting the results to be attained. To the clock frame is secured the extension frame 21, and the shaft 19 is extended therethrough and journalled at 22. This shaft extends through the disc 23, Figs. 3 and 4, which function as one element of a thrust bearing, reacting against the frame 21. To the end of the shaft is rigidly secured the companion disc 24, and a plurality of balls are preferably interposed between the discs to minimize friction of rotation. To the face of the disc 24 is rigidly secured the insulation disc 25, and inset therein is the metal switch segment 26, which functions as the shaft 19 rotates in unison with the center arbor 13 through the gear train described. Enclosing the discs is the chambered element 27, rotatable concentrically about the discs 24, 25, but angularly separated therefrom. This element is retained in axial alignment by means of the disc 23, which serves as a journal therefore, and its axial movement is limited by the ring 28 secured to the frame 21.

The element 27 in its end, with the eccentrically disposed opening 29, in which are mounted the insulated terminals 30-31, one of which is in constant engagement with the switch segment 26, preferably at its axis of rotation, the other being angularly adjustable thereabout as the chambered element is rotated as will be described. This element 27 is provided with the annular gear 32, meshing with a gear 33 of equal size, rigidly secured to the shaft 34, which is journaled at 35-36 in the extension frame 21. By means of the knob 37 secured to the other end of the

shaft 34, the indicator 38 also rigid with the shaft, may be rotated to align with markings on the dial 39, for the purpose indicating the time at which the circuit will close and the lights operate. The dial 39 is marked to correspond with the limits within which the switch will operate to close the circuit, and as the indicator is swung to indicate the particular time at which it is desired to close the circuit, the chambered element 27 is correspondingly rotated, and the radial position of the terminal 31 varied accordingly. The switch segment 26 is radially positioned in fixed relation to the timing mechanism of the clock, and is coordinated with the terminal 31 to close the circuit at the time indicated on the dial 39. After the circuit is closed, it so remains during the time the segment is rotating in contact with the terminal 31, the terminal 30 as stated being always engaged. In the drawings the range of the dial is shown as six hours, and includes a segment of 180 degrees subdivided accordingly. With the dial so spaced, the included angle of the switch segment must be less than 180 degrees, in order that the setting may be made a full six hours in advance of the closing of the circuit. The time during which the circuit will remain closed is therefore dependent on the included angle of the segment, and in this case cannot exceed six hours.

If the included angle of the segment be lessened, the range of the dial may be correspondingly increased, the reverse being obviously true. As the time of setting the indicator together with the time during which the circuit remains closed, is limited by one complete cycle of the timing mechanism of the clock, and as the time during which the lights may be required may over run, provision is made as will be presently described, to shunt the electric current directly through the lights to provide continuous lighting as long as the light switch of the automobile is in "on" position.

In Fig. 5 I have shown diagrammatically, the lighting circuit of an automobile in which I have incorporated my device, and reference thereto will explain the operation and action thereof. In this figure, the clock A and the controlling device B are mounted as a unit on the instrument board of an automobile. The headlights D and the tail light E are in circuit with the battery F, from which extends wiring to the terminals and lights. The indicator 38 is swung to indicate on the dial 39, the time at which it is desired that the circuit be closed and the lights lit. This may be done at any time within the range of the dial, which in conjunction with the switch segment, permits the terminal 31 to engage the insulation disc 25, as it rotates in unison with the center arbor 13 of the clock. The light switch G of the automobile being turned to "on" position, the terminal 31 will

ride on the insulation until engaged by the switch segment inset therein, at which time the clock hands and the indicator agree as to time, and the circuit is closed and will so remain until the segment rotates out of engagement with the terminal 31. 70

As the terminal 30 engages the switch segment permanently, approximately at its axis of rotation, there is a minimum resistance to its rotation, and as the terminals are at all times insulated from the clock mechanism, no interference with the accuracy of the clock is possible from electric action. Under the above conditions the lights would go out when the circuit was broken as described, and I have made provisions to anticipate that event and continue the lighting. 75

The main purpose of this device is to automatically close the light circuit at a required time, and a reasonable time is provided for maintaining the circuit in the absence of the operator. It is necessary however to provide for continuous lighting after the lights are on and before the circuit is broken. I therefore provide another switch H in the circuit which operates to shunt the current through the usual circuit at the will of the operator. When employing my device for predetermining the time of lighting, this switch is in "off" position, and the electric current will operate as described. If the switch H is turned to "on" position at any time thereafter, the circuit through the lights will be direct and without reference to the further operation of the device, and the lights will remain on until the light switch G is thrown in the usual manner. This device may be equally well employed as a circuit breaker by changing the relation of the terminal 31 and the switch segment engagement. This may be readily accomplished by loosening the ring 28, disengaging the gears 32-33 from each other, and rotating the gear 32 to establish a reverse relation of the terminal 31 and the segment 26 and the indicator 38. The gears may then be engaged and the ring secured in place. The indicator will then register the time at which the closed circuit will be broken. 90

Having thus described my invention, I claim: 100

1. In a time controlled switch, having a switch member rotatable in fixed relation to timing mechanism and with a terminal holder concentrically adjustable in relation to the axis of the switch member, the combination therewith of a pair of insulated terminals mounted in the holder, one in operative engagement with the switch member, the other adapted to be engaged thereby to close the circuit, as the switch member is rotated by the timing mechanism; means for rotating the terminal holder to adjust the angular relation of the terminals and the switch member; 110 120 125 130

for the purpose of closing the electric circuit at a predetermined time in the cycle of the timing mechanism.

2. In a time controlled switch, having a switch member rotatable in fixed relation to timing mechanism and with a terminal holder concentrically adjustable in relation to the axis of the switch member, the combination therewith of a pair of insulated terminals mounted in the holder, one in operative engagement with the switch member, the other adapted to be engaged thereby to close the circuit, as the switch member is rotated by the timing mechanism; an indicator operatively connected with the terminal holder; means for rotating the terminal holder and the indicator to adjust the angular relation of the terminals and the switch member; for the purpose of closing the electric circuit at a predetermined and preindicated time in the cycle of the timing mechanism.

3. In a time controlled switch having a switch member rotatably coordinated with, and in fixed relation to timing mechanism, a terminal holder concentrically adjustable in relation to the axis of the switch member, an indicator, and operative connections between the terminal holder and the indicator through which movement of the indicator is transmitted to rotate the terminal holder to adjust the angular relation of the terminals and the switch member, the combination therewith of a pair of insulated terminals mounted in the holder, one in operative engagement with the switch member, the other adapted to be engaged thereby as it is rotated by the timing mechanism, as and for the purpose described.

4. In a time controlled switch, in combination with timing mechanism, a switch member rotatably coordinated therewith and insulated therefrom; a pair of insulated terminals, one in operative engagement with the switch member, the other adjustable to be engaged thereby to close the circuit as the switch member is rotated by the timing mechanism; for the purpose of closing an electric circuit at a predetermined time in the cycle of the timing mechanism.

5. In a time controlled switch, in combination with timing mechanism, a switch member movably coordinated therewith and insulated therefrom; a pair of insulated terminals, one in operative engagement with the switch member, the other adjustable to be engaged thereby to close the circuit, as the switch is moved by the timing mechanism; an indicator; operative connections between the indicator and the terminals, by means of which the angular relation of the terminals and the switch member may be adjusted; for the purpose of closing the electric circuit at a pre-indicated time in the cycle of the timing mechanism.

6. In a time controlled switch, including

as elements a movable switch member a pair of terminals, one in engagement therewith, the other adjustable relative thereto to close the circuit as the switch is moved, and an indicator; the combination therewith of operative connections between the indicator and the terminals, adjustable to position the terminals relative to the switch member such that the electric circuit may be either closed or opened at a pre-indicated time depending on the adjusted position of the terminals relative to the switch member.
